United States Patent Office

Des. 185,536
Patented June 23, 1959

185,536

AUTO BODY FILE HANDLE

Rudolf F. Csada, Summerville, Ontario, Canada

Application August 29, 1957, Serial No. 47,549

Term of patent 14 years

(Cl. D54—13)

FIG. 1.

FIG. 2.

FIG. 3.

FIG. 4.

Fig. 1 is a top plan view of an auto body file handle showing my new design;

Fig. 2 is a side view thereof;

Fig. 3 is a bottom view thereof; and
Fig. 4 is an end view thereof.

I claim:

The ornamental design for an auto body file handle, as shown.
